REMOTE CONTROL SYSTEM

Lloyd V. Lewis, Pittsburgh, Pa., assignor to The Union Switch & Signal Company, Swissvale, Pa., a corporation of Pennsylvania

Application March 11, 1939, Serial No. 261,241

9 Claims. (Cl. 177—353)

My invention relates to remote control systems, and more particularly to the communication or line circuits for such systems.

My invention is particularly adapted for though in no manner limited to centralized traffic control systems for railroads in which a train dispatcher's office or other suitable point of control is connected with a plurality of field stations by line wires, over which code signals are transmitted at times for controlling selected devices at the stations, and at other times for indicating the condition of station devices at the office.

My invention is an improvement upon the centralized traffic control system disclosed in my pending United States application, Serial No. 600,786, filed March 23, 1932, for remote control systems, which corresponds with the United States Letters Patent No. 2,229,249, issued January 21, 1941.

One object of my invention is to provide additional communication channels over the line wires of the centralized traffic control system, the additional channels being suitable, for example, either for telephone communication, or for code signaling, or for both purposes. A specific object of my invention is to so arrange the system of my prior application that it may be used in connection with a normally open, or bridged line circuit.

A further object of my invention is the provision of an arrangement of apparatus which will permit the line circuit of the centralized traffic control system to be used by other code systems employing different codes, without interference, even though two or more codes are initiated simultaneously.

In the specific embodiment herein illustrated, the code system of my prior patent hereinbefore referred to is so modified that the line circuit is rendered available for voice frequency communication and also for code signaling by means of selector systems of the code wheel type, such systems being well known, as shown, for example, in the Field Patent No. 1,343,256 or in the Gill Patent No. 1,970,301.

Other objects, purposes and features of my invention will be pointed out as the description proceeds.

I shall describe one form of apparatus embodying my invention and one modification thereof, and shall then point out the novel features thereof in claims.

Referring to the accompanying drawings, Fig. 1 illustrates the line circuit for a centralized traffic control system and associated apparatus

arranged in accordance with one form of my invention, while Fig. 2 illustrates an alternative form of apparatus suitable for use at an intermediate field station in the system of Fig. 1. Figs. 3 and 4 show the local circuits at the office and station, respectively, for the system of my invention, these circuits being generally similar to those of my Patent No. 2,229,249, hereinbefore referred to, except that as here shown they have been arranged in a more condensed form and have been modified to conform with Fig. 1.

Similar reference characters refer to similar parts in each of the two views.

Referring to Fig. 1, the reference characters 15 Y, Z designate the line wires of the system which extend from the point of control, usually a train dispatcher's office, as indicated by the legend "Office" on the drawing, through each of a plurality of field stations of the centralized traffic control system, in turn. Since the field stations are generally similar, but one is shown in order to simplify the drawings, this being identified on the drawing by the legend "CTC Station."

The line circuits are arranged as shown in the

Field patent hereinbefore referred to in that the telephone and code signaling apparatus are bridged across the line wires Y, Z. As shown, a voice frequency communication channel extends from the telephone apparatus 19 at the office

20 through a high pass filter illustrated as the condensers 20 to line wires Y, Z thence through similar condensers 20 and telephone apparatus 19 at the distant end of the line, as shown on the drawing, or through a jack 24 to telephone apparatus, not shown, at an intermediate point

30 such as at one of the field stations. The selector apparatus is also arranged as shown in the Field patent, and this comprises a plurality of code wheels 89, 90 at the office, each of which when

40 manually wound up and released makes one revolution during which a code sending relay 86 is energized over a circuit including the code wheel 89 or 90 and contact 96 to connect a line battery 85 through the contacts of a pole changer relay 87, a low pass filter 18 and choke coils 17, to the line wires Y, Z. As the code wheel rotates, relay

45 87 is intermittently energized over a circuit including contacts 96, 97 in accordance with the arrangement of the code wheel teeth to deliver a code of direct current impulses of alternately reversed polarity to the line wires Y, Z.

These impulses selectively control the code-wheel selectors 72 which are located as required at different points along the line. Since all the selectors are similarly arranged, but one is shown

in order to simplify the drawings, this being located at a point designated "Selector station" on the drawing.

Each selector 12 is connected across the line in the usual manner through a condenser 14 and a choke coil 17, and may be used to operate a call bell 16, a stick relay F, or for other purposes. The relay F, for example, may be used to govern railway traffic apparatus as shown for the similar relay F in the Wallace Patent No. 1,650,575.

The remaining relays of Fig. 1 are a part of my centralized traffic control system, as shown in detail in Figs. 2 and 3 and with the exception of the added relay V these relays bear the same designation as the corresponding relays of my patent hereinbefore referred to and the purposes and detailed mode of operation of these relays and of the coding units which they control may be ascertained from the patent.

The circuits of the system as arranged in accordance with the present invention differ, however, in a number of respects from those of the patent and these differences will now be explained.

The relays OR and R are the line relays of the system which control coding units for selectively receiving code signals from the line and for also governing the operation of the relays OT and T, which are the transmitting relays for delivering code signals to the line. In the patent, a normally closed line circuit is used which includes the windings of the line relays OR and R and back contacts of the transmitter relay OT and of the master relay M at each station, all in series. This arrangement has been changed in accordance with the present invention and in Fig. 1 and likewise in Figs. 2 and 3 the line relays OR and R, which are to be understood as being high resistance biased polar relays, are bridged across the line through choke coils 17 for preventing the diversion of voice frequency currents through the relays, and the transmitter contacts are the normally open front contacts of the relays OT and T which are bridged across the terminals of the line relays, and therefore across the line, through low-pass filters 18 which limit the rate of change of the code signaling currents to values below the voice frequency band. As in the patent, each line relay R controls two slow release relays L1 and L2 which in turn control a third slow release relay LB. For an understanding of the present invention it is believed to suffice to point out that all these relays are normally deenergized, but that as long as the line relay R is intermittently operated by code signals one or the other of the relays L1 or L2 will remain picked up, that relay LB remains picked up for the duration of the code, and that the office relays OL1, OL2 and OLB are similarly governed by relay OR. Furthermore, relays OL1 and L1 are the last to release at the end of a code, and serve to interpose a pause to properly space two successive codes. Since the line circuit is normally open, the codes are reversed with respect to those of the patent, that is, in the present instance the line open condition corresponds to the line closed condition in the codes of the patent, and vice versa, and it will be seen by comparison with the patent that the connections of the line relay contacts to the relays of the coding unit are correspondingly reversed.

Each code delivered to the line wires Y, Z by a transmitter relay OT or T consists of a series of either 7 or 8 impulses, each of which may be

relatively short or long, the intervening line open intervals also being relatively short or long to characterize the code.

One feature of the present invention relates to the means for preventing interference between different codes, and the manner in which this is accomplished will now be pointed out.

As explained in the patent, a control code for governing the railway traffic control apparatus at a selected field station of the CTC system, in accordance with the positions of the corresponding control levers at the office, is initiated by picking up a start relay identifying the code to be transmitted, such as relay 234ST, Fig. 3, to complete a circuit for the office master relay OM, which circuit may be traced in Fig. 1 from one terminal B of a suitable source of current over a front contact of the start relay, back contacts of relays OL1 and OL2 through relay OM to the other terminal C of the same source. In the form of the apparatus disclosed herein, relay OM upon becoming energized connects the line battery 85 to the contacts of the office transmitting relay OT. Relay OM completes circuits, as shown in Fig. 3, for intermittently energizing relay OT to deliver the desired code to the line wires Y, Z to operate the line relays OR and R. The apparatus at the office and at one station only responds selectively to such code by closing various circuits shown in Figs. 3 and 4 to pick up a selector relay such as 234S at the office and a similar relay S at the selected station and then other relays controlled by relay S are controlled in accordance with the condition of control levers associated with relay 234S. The first impulse delivered to the line by relay OT by energizing relay OR effects the successive energization of relays OL1, OL2 and OLB, the latter relay completing a stick circuit extending to terminal B, for holding relay OM energized for the duration of the code. The stick circuit for relay OM has been modified as shown herein by including a back contact of the code sending relay 86 of the selector system.

The circuits for relay 86 in Fig. 1 differ somewhat from those of the corresponding relay of the Field patent. Thus in Fig. 1, relay 86 has a pick-up circuit extending from terminal B, back contacts of relays OL1, OL2 and 86, code wheel 89 or 90, contact 96, relay 86 to terminal C, which is closed upon the release of the code wheel only if no code is then being delivered to line relay OR so that relays OL1 and OL2 are both deenergized. Relay 86 upon becoming energized completes a stick circuit extending to terminal B over its own front contact which is independent of relays OL1 and OL2 and which is opened at contact 96 upon the return of the code wheel to normal at the end of the code delivered by the pole changer 87.

It will be apparent from the foregoing that neither the release of a code wheel nor the operation of a start relay at the office is effective to initiate a code unless relay OR has been deenergized for a time sufficient to effect the release of relay OL1, indicating that the line is free, while if both systems are initiated at the same time, the selector system takes precedence, relay OM of the CTC system being released upon the energization of relay 86 of the selector system.

Considering now the apparatus at the CTC station of Fig. 1, it is to be understood that an indication code, that is, a code indicating a change in the condition of the railway traffic governing devices at the station, is initiated by energizing

a station start relay such as the relay ST of Fig. 4 to complete a pick-up circuit for the master relay M.

Relay M, upon becoming energized, at its upper front contact completes a circuit for a vibrator relay V, Fig. 1, and since this circuit includes also a back contact of relay V, that relay is caused to vibrate to close its front and back contacts alternately as long as relay M remains energized, that is, for the duration of the code. The upper contacts of relay V connect terminal B of the local direct current source alternately to the two end terminals of the primary winding of the step-up transformer 12 which has its midpoint connected to the other terminal C of the direct current source, causing current impulses of alternately opposite polarity to be impressed upon the primary so that a relatively high alternating current voltage of a frequency the same as the rate of vibration of relay V is developed across the secondary terminals of transformer 12. This voltage is rectified by the operation of the lower contacts of relay V, and the resulting rectified current is delivered to the terminals BE and CH and thence over contacts of relay M to the code transmitting contacts of relay T. Relay V and transformer 12 thus provide a relatively inexpensive and convenient local source of line current which is generated only when needed, avoiding the necessity for providing a high voltage line battery such as 85 at each field station. Relay M, upon becoming energized, completes circuits as shown in Fig. 4 for intermittently energizing relay T to deliver an indication code to line wires Y, Z through the low-pass filter 18 and choke coils 17, this code operating the line relays OR and R, but as explained in the patent, only the coding units at the office and at the transmitting station respond selectively. At the office, a selector relay such as 2348 becomes energized, and likewise relay S at the transmitting station, these relays controlling the operation of indication devices at the office in accordance with conditions at the station.

Relay R at the transmitting station governs the transmission of the code by relay T at that station, while relay R at each station effects the energization of the associated relays L1, L2 and LB. Relay LB at the transmitting station upon becoming energized completes a stick circuit for holding relay M energized, which circuit as shown in my patent extends over front contacts of relays M and LB, and also over a back contact of relay 16 which opens to release relay M at the end of the code. This circuit as shown in Fig. 4 differs from the corresponding circuit of my patent in that the connection to terminal B is not made at the contact of relay 16 but the circuit includes two branches, one extending to terminal B over a front contact of relay T and the other extending to terminal B over a back contact of relay T and the right-hand contact of the line relay R. Since relay T controls R, these contacts operate approximately in unison to maintain the stick circuit for relay M closed substantially continuously so as to maintain relay M picked up as long as the code to which relay R responds is the same as that delivered to the line by relay T.

In order to distinguish between controls and indications, each control code is arranged to begin with a relatively long impulse and each indication code with a relatively short impulse, the apparatus at each station including a relay E which is selectively responsive to a long first impulse of a code and which is required to be energized in order to condition the station appa-

ratus to respond selectively to the code. It follows that a code delivered to the line circuit by any station, since it begins with a short impulse, will operate the receiving apparatus at the office but not that at any other station. Furthermore, in the event the office and one or more stations initiate codes at the same time, current will be maintained on the line by relay OT after relays T have released and consequently the front contact of relay T and the right-hand contact of relay R at each transmitting station will both be open long enough to release the relay M at such station, so that the office transmitter will be the only one which continues in operation, the station relays E also being energized to condition the stations to selectively respond to the code transmitted by the office.

It will be clear, therefore, that the arrangement just described prevents interference in the event of simultaneous initiation of codes from the office and one or more stations, and that control codes take precedence over indication codes when both are initiated simultaneously.

It may also happen that a calling key is operated to initiate a selector code at the same time that one or more stations initiate indication codes.

By reference to Fig. 1 or to the Field patent, it will be seen that the code wheels 89, 90 are arranged to apply current to the line circuit by the energization of relay 86, prior to the transmission of code impulses by relay 87, for an interval similar to a long step of the code. By reference to Fig. 1 it will be seen that the connections to battery 85 have been arranged so that the initial impulse of a selector code is of the same polarity as the first impulse of a CTC code. This impulse is arranged to be long enough to lock out the station transmitters, so that selector codes take precedence over indication code when both are initiated simultaneously.

Another condition to be considered is the mode of operation when two or more stations initiate indication codes at the same time. When this occurs, the transmitter relays T are held in synchronism by their respective line relays R as long as the code elements of the different codes are alike, but since the codes differ in at least one element, a step will be reached which is long in the code delivered by one transmitter and short in the code delivered by another. If this occurs on a line-closed, or odd-numbered step, the result will be the same as when it occurs on the first step as above described, and the station having a long impulse to transmit, will take precedence, the master relay M at the other station releasing to discontinue the operation of the transmitter at that station. If it occurs on a line-open, or even-numbered step, relay T at the station having a long interval to transmit will remain released after the contact of relay R at that station is operated to the left by the next impulse following the short interval of release of relay T at another station, to release relay M. It follows that a station having a short line-open interval to transmit takes precedence over one having a long interval to transmit. In any case, it is evident that but one station transmitter will continue in operation to the end of the code and that but one code will be delivered to the office at a time, the several codes being delivered to the line circuit one at a time in a predetermined order of code superiority, without interference.

A similar arrangement for locking out the stations of a system employing a normally closed series line circuit is disclosed in the Snavely,

Miller and Jackel application, Serial No. 31,592, filed July 16, 1935, for Remote control systems, now Patent No. 2,183,155, issued December 12, 1939.

There remains to be considered the effect of the different codes upon the receiving apparatus of the CTC system and upon the selectors. In my CTC system, the selection of a station or of an office panel is effected by a combination of three long and four short steps directly following the first step, and each of the remaining five or seven steps may be either short or long.

The selector code includes only two long steps out of a total of 32 or less. In the Field patent, the total number chosen for illustration is 15 but a total of 17 or 27 steps is used in practice. The selectors are immune to ordinary Morse signals because the latter contain more than two long steps in any 17 successive steps, and for the same reason they are non-responsive to the CTC codes. Likewise the CTC receivers are non-responsive to the selector codes because the latter do not contain three long steps in any group of eight, as required to effect a selection in the CTC system. It follows, therefore, that the total number of codes provided by both systems may be used, without interference.

Another arrangement for preventing interference in the event that the transmitters at two or more stations are initiated at the same time may be used in the system of Fig. 1, this comprising an arrangement for sectionalizing the line as in the system of my patent.

This alternative arrangement is illustrated in Fig. 2, and referring to this view, it will be seen that the line wires Y, Z, which extend to the control office are carried through each intermediate station over back contacts of the station master relay M to the line wire sections Y₁, Z₁ which, it is to be understood, extend to the next station to the right, while at the station most remote from the office they extend to the telephone apparatus 19 at that end of the line, as in Fig. 1. In order to maintain the voice frequency communication channel while relay M is energized, the back contacts are bridged by high-pass filters or condensers 21, in the manner disclosed in the Baughman application, Serial No. 256,976, filed February 17, 1939, for Remote control systems, now Patent No. 2,208,446, issued July 16, 1940.

When relay M picks up to initiate transmission from the station shown in Fig. 2, relay V is intermittently energized to generate direct current as already described, but in Fig. 2 as long as relay M remains energized, this current is supplied from terminals BH and CH over the front contacts of relay M to the line wires Y₁, Z₁ extending to the stations more remote from the office. The contacts of the line relays at such stations are operated to the left, just as if the office apparatus had initiated a code. Since terminals BH and CH remain connected to the more remote section of the line for the duration of the code, this section serves as a source of code signaling current for the transmitting station, current from terminals BH and CH being delivered through the filter 18 and the contacts of relay T to relay R, and also through the choke coils 17 to line wires Y, Z and thence to the office, each time relay T becomes energized. It will be seen that as long as a station is transmitting a code to the office, the transmitters at the more remote station are held locked out by the current de-

livered to line wires extending to these stations by relay M at the transmitting station.

In the event the office and a station initiate codes simultaneously in the system of Fig. 2, relay E at the first station will become selectively energized due to the long first impulse delivered from the office as already explained, and relay E at each more remote station will become energized due to the similar impulse delivered to line wires Y₁, Z₁. When relay E at the first station picks up, its front contacts bridge condensers 21 in the line circuit, and the current delivered to line wires Y₁, Z₁ will then be supplied also to line wires Y, Z after relay T has released, thereby maintaining the office line relay OR reversed even though the office transmitter relay OT releases, until relay M releases. The office transmitter is thus held on the first step of the code until relay M releases to disconnect the station source of current from the line circuit. It will be evident from Fig. 1 that relay M will be released by relay E, the circuits for relay M in Fig. 2 being the same as in my patent, these circuits having been already explained in connection with Fig. 1. It will be seen, therefore, that when relay M releases, the receivers at the office and at all stations will have completed the first step of a control code and are ready to advance to the second step under the control of the office transmitter relay OT, which is then free to complete the code.

In view of the foregoing description it is believed that it will be apparent that the apparatus will also function properly in the event the office and two or more stations initiate codes simultaneously, and that the several codes will be transmitted one at a time in a predetermined order without interference.

Selectors of the types hereinbefore referred to are used quite extensively by the railroads, and there are many train dispatcher's telephone lines in use over which selectors are controlled. In accordance with the present invention such circuits are rendered available also for the control of centralized traffic control apparatus, rendering installations of the latter commercially feasible, in many cases, under conditions which otherwise would not be justified on account of the relatively large cost of the line wires if a separate line circuit were required.

In many instances the office equipment of the CTC system will not be directly under the control of the train dispatcher or operator who manipulates the selector calling keys, but will be in charge of a different operator. In such cases it is desirable to indicate by suitable means adjacent the calling keys when the line is free so that a calling key will not be operated when the line is in use. To this end I provide a normally energized indicator lamp 1E adjacent the selector calling keys which is controlled over back contacts of relays OL₁ and OL₂ as shown in Fig. 1. This lamp will be extinguished whenever a code is being delivered to the line circuit either by the CTC apparatus or by a calling key. In order to definitely inform the operator of the delivery of a selector code to the line circuit, I provide a second lamp 2E which is controlled by relay 86 so as to be lighted only while a selector code is being transmitted.

Although I have herein shown and described but one form of my invention and one modification thereof, it is understood that various changes and modifications may be made within the scope

of the appended claims without departing from the spirit and scope of my invention.

Having thus described my invention, what I claim is:

1. In a remote control system, an office and a plurality of stations, a normally deenergized master relay at each station, a normally open line circuit extending from the office through said stations and including back contacts of the master relay at each station, local sources of line current at each station, means effective when the master relay at an intermediate station is energized to supply steady current from the source at said station to the line circuit portion extending to more remote stations and to also supply current from said source interrupted in accordance with a code to the line circuit portion extending to the office, and means for energizing said master relay for the duration of such code effective only when the line circuit at such station is deenergized.

2. Remote controlling apparatus comprising a single line circuit connecting a plurality of stations, a line relay at each station connected across said line circuit, a normally open code transmitting contact and a local source of line current at each station, means at each station effective only if the line relay at such station is deenergized for at times connecting said local source across said line circuit through said code transmitting contact and for disconnecting the portion of said line circuit extending beyond said station, and means for steadily energizing said portion as long as it remains disconnected.

3. Remote controlling apparatus comprising a single line circuit normally connecting an office and a plurality of stations, a line relay connected across said line circuit at each station, a local source of line current and a code transmitting contact at each station, means at each station effective only if the line relay at such station is not energized for connecting the local source across the line circuit through the associated transmitting contact and for disconnecting the portion of the line circuit extending to stations more remote from the office, means for subsequently operating said transmitting contact to deliver a code to the remaining portion of said line circuit, means for steadily energizing said disconnected portion of the line circuit while said code is being delivered, and means for operating upon the completion of said code to restore the normal line circuit.

4. In a remote control system, a normally open line circuit extending from an office to a plurality of stations, a normally deenergized line relay bridged across said line circuit at each station, a local source of current and a code transmitting contact adapted to be connected in series across said line circuit at each station, a master relay at each station, a pick-up circuit for each master relay closed only when the associated line relay is deenergized, a stick circuit for each master relay, means effective when each master relay is energized for connecting said local source across the portion of the line circuit extending to stations more remote from the office and for interposing means blocking the flow of current from said source between said portion and the remainder of said line circuit, and means for operating the associated transmitter contact when such master relay is energized to deliver a code to said office.

5. In combination, an office and a station connected by a single line circuit, a remote con-

trol system having a plurality of code transmitters including one at said office and one at said station each operable only if initiated when the line is free, to deliver impulse codes to said line circuit, starting means for each transmitter free to be actuated at any time to condition that transmitter to deliver its code, indication means at the office effective for indicating when the line is free, a plurality of manually releasable code wheels at said office, an additional code transmitter at said office operable immediately in response to the manual release of a code wheel but only if the code wheel is released when the line circuit is free, to deliver other impulse codes to said line circuit, interference preventing means controlled over said line circuit in response to the first impulse of a code and effective to disconnect said station transmitter from said line circuit during the transmission of a code initiated simultaneously and jointly by said station transmitter and by the office transmitter of said remote control system or by said additional transmitter, means for disconnecting the office transmitter of said remote control system from said line circuit during the transmission of a code initiated simultaneously and jointly by said office transmitter and said additional transmitter, and storing means associated with each remote control system transmitter for initiating its operation as soon as the line is free if the starting means for such transmitter is actuated when the line is in use or if such transmitter has been disconnected from the line circuit by the operation of another transmitter.

6. In combination, an office and a station connected by a single line circuit, a remote control system having a plurality of code transmitters including one at said office and one at said station each operable when initiated, to deliver impulse codes to said line circuit, a plurality of manually releasable code wheels at said office, an additional code transmitter at said office operable immediately in response to the manual release of a code wheel, to deliver other impulse codes to said line circuit, line relays at said office and at said station, means for initiating each code transmitter to deliver its code effective only when the line is free as manifested by the condition of the associated line relay, means for interrupting the transmission of a code by the transmitter at said station when the response of the associated line relay is not in accordance with the character of the first element of such code, means for interrupting the transmission of a code by the office transmitter of said remote control system when said additional transmitter is initiated at the same time, and storing means associated with the transmitters of said remote control system for storing each such interrupted code for subsequent transmission when the line is again free.

7. In combination, an office and a station connected by a normally open line circuit, a remote control system having a control code transmitter at said office operable when initiated to deliver impulse codes to said line circuit in each of which the first impulse is relatively long, and also having an indication code transmitter at said station operable when initiated to deliver impulse codes to said line circuit in each of which the first impulse is relatively short, a plurality of manually releasable code wheels at said office, an additional transmitter at said office adapted to be initiated in response to the manual release of a code wheel to deliver an initial relatively long impulse to said line circuit followed

by a code characteristic of the operated code wheel, line relays at said office and station responsive to the code impulses in said line circuit, means for initiating each code transmitter effective only when the line is free as manifested by the steadily deenergized condition of the associated line relay, means for interrupting the transmission of a code by the transmitter at said station in the event the station line relay fails to release in response to the operation of that transmitter for terminating the first impulse of such code, means for interrupting the transmission of a code by the office transmitter of said remote control system when said additional transmitter is initiated at the same time, and means associated with the transmitters of said remote control system for storing each such interrupted code for subsequent transmission when the line is again free.

8. In combination, an office and a station connected by a single line circuit, a remote control system having a plurality of code transmitters including one at said office and one at said station each operable when the line is free, to deliver impulse codes to said line circuit, a plurality of manually releasable code wheels each operable if manually released when the line is free, to immediately deliver other impulse codes to said line circuit, interference preventing means effective when a code is initiated by the station transmitter and by the office transmitter of said remote control system or by a code wheel at the same time for interrupting the operation of said station transmitter, other interference preventing means effective when a code is initiated by a code wheel and by the office transmitter of said remote control system at the same time for interrupting the operation of said office trans-

mitter, and storing means associated with the transmitters of said remote control system for storing each such interrupted code for subsequent transmission when the line is again free.

- 5 9. In a communication system having an office and at least two stations connected by a line circuit, the combination with a remote control system having a plurality of code transmitters including one at said office and one at each station each operable when initiated to deliver an impulse code to said line circuit, and having starting means for each transmitter free to be operated at any time to condition such transmitter to transmit its code but effective to initiate its operation only when the line circuit is free, and also having storing means effective to maintain each actuated starting means in its actuated condition until the corresponding code has been fully transmitted, said remote control system also including interference preventing means effective when two or more transmitters are initiated simultaneously and they jointly deliver the first impulse of a code to the line circuit, to prevent further operation of all but one during such code, of an additional transmitter for delivering other impulse codes to said line circuit, together with manually operable means free to be operated at any time but effective only if operated when the line is free, to initiate the operation of said additional transmitter, and interference preventing means effective when said additional transmitter and one or more transmitters of said remote control system are initiated simultaneously and they jointly deliver the first impulse of a code to said line circuit, to prevent further operation of any remote control system transmitter during such code.

LLOYD V. LEWIS.
